UNITED STATES PATENT OFFICE.

JOHN HOWARD McELROY, OF CHICAGO, ILLINOIS.

AUTOMATIC BLANK-FEEDING APPARATUS.

SPECIFICATION forming part of Letters Patent No. 793,212, dated June 27, 1905.

Application filed August 27, 1903. Serial No. 170,955.

To all whom it may concern:

Be it known that I, JOHN HOWARD McELROY, a resident of Chicago, in the county of Cook and State of Illinois, have invented certain new and useful Improvements in Automatic Blank-Feeding Apparatus, of which the following is a specification.

My invention is concerned with certain new and useful improvements in automatic blank-feeding mechanism which I have devised primarily for feeding the blanks to a can-body machine, but which may be employed for any similar purpose.

I will first describe the mechanism in which I have embodied my invention and finally in the claims point out what I consider to be the novel features thereof.

To illustrate my invention, I annex hereto three sheets of drawings, in which the same reference characters are used to designate identical parts in all the figures, of which—

Figure 1 is a side elevation of my invention as applied to a can-body lock-seamer of any reciprocating-feed type. Fig. 2 is a front elevation of the same. Fig. 3 is a central longitudinal section. Fig. 4 is a top plan view. Fig. 5 is a sectional view on the line A A of Fig. 4. Fig. 6 is a detail illustrating a modification. Fig. 7 is a diagrammatic view of the electrical connections employed in connection with the form previously illustrated. Fig. 8 is a detail showing the contacts. Fig. 9 is a diagrammatic view similar to Fig. 7, but illustrating a modification; and Fig. 10 is a diagrammatic view illustrating a modification and the electrical circuits employed in connection with apparatus for controlling the operation thereof.

In carrying out my invention I employ a pair of frame-pieces 11, which are suitably secured on the framework 12 of the machine with which the mechanism is employed. A transverse piece 13 connects the side pieces and serves as a support upon which the corner-pieces 14 are adjustably secured in order that the apparatus may be adjusted for different-sized blanks. The two corner-pieces 14, together with the front piece 15, which is pivotally mounted on the rod 16, connecting the two side pieces 11, form the blank-holder.

The front piece 15 is held rigidly in a vertical position by the bar 16^a coöperating with apertures 17 in the frame-pieces, and by removing the bar 16^a the front piece 15 can be swung down to insert a fresh supply of blanks. 55 The blanks are supported upon the vertically-movable table 18, which is secured to one or more rack-bars 19, which are raised slowly by the gear-wheels 20, secured on the shaft 21, journaled in suitable bearings in the side pieces 11. The roller 22, also journaled in the side pieces, serves to hold the rack-bar in engagement with the gear-wheels. To rotate the shaft 21 at the proper rate of speed to keep the blanks 23 at the proper level as they 65 are carried away one by one, I employ the lever 24, which is swung a certain distance at each operation by the cam 25, secured on the shaft 26, which is operated by mechanism to be subsequently described. A pawl 27 on the lever 24 engages the teeth of a ratchet-wheel 28 to advance the same one or more notches at each rotation of the shaft 26. A detent-pawl 29 holds the ratchet-wheel in its advanced position. 75

A pair of angular guiding and supporting pieces 30, supported from the main machine, extends out over the blank-holder, the horizontal flanges being cut away just over the holder to permit a blank to be raised without interfering therewith. The blanks are fed forward by the reciprocation of the bars 31, extending from the main machine and provided with the yielding spring-pressed pawls 32, which advance the blanks forward step by 80 step, as is customary in this class of devices. To raise the blanks, I employ adhering lifters 33, which are secured upon the bar 34, extending across the top of the blank-holder and very loosely pivoted by the ears 35 upon 90 the pair of arms 36, which is pivoted at 37 on stub-shafts supported by the side pieces 11. To raise and lower the arms 36, and thereby the lifters 33, at each operation of the machine, I journal in the side pieces 11 a shaft 95 26, previously referred to, which has a pair of cams 38 on its ends in the proper plane to coöperate with the arms 36, preferably through the medium of the antifriction-rollers 39, mounted on said arms above the U- 100

shaped recesses 40, formed therein, to permit the arms 36 to be lowered without interfering with the shaft 26. Rigidly secured to the cross-piece 34, preferably by the arm 41, by 5 which it is loosely fulcrumed at one end, is the arm 42, the outer end of which is screw-threaded and provided with the weight 43, which can be secured thereon in any desired position of adjustment to cause the arm 42 10 and its weight to counterbalance the weight of the cross-piece 34, the lifters 33, and the blank 23. This weight is so adjusted that if the lifters carry up a single blank they will not be overweighted and the arm 42 will 15 remain resting on the shaft 26. If on account of the adhesion of the blanks two or more are lifted simultaneously, they will overbalance the arm 42 and weight 43, and as the parts are raised the lifters will swing down relatively to the arms 36, and this swinging movement is utilized to release the blanks before the carrier-bars 31 can pass beneath them, and thus carry more than a single blank to the machine. If the lifter is pneumatic, 20 as illustrated in Fig. 6, where 33^a is the customary pneumatic lifter, the release of the adhesion may be effected by having the valve-stem 44 extend over a rod 45, connecting the outer ends of the arms 36^a. From a consideration of this construction it will be apparent that if the front end of the balance is 25 overweighted by the adhesion of more than one blank as the arms 36^a are raised the bar 34^a swinging down relative to the arms 36^a 30 will cause the valves 44 to be lifted and the adhesion of the lifter released.

The features of my invention which have hitherto been described may be employed in connection with any kind of a lifter, such as 40 any kind of a suction device or a permanent magnet; but I prefer to employ electromagnets as lifters and energize them at each operation of the machine, preferably by closing the circuit in which they are included.

45 The electromagnets 33 are of any desired construction, but preferably have their cores made of Swedish iron, which demagnetizes quickly to allow the blanks to drop when the circuit is broken with the parts in the position shown in Fig. 3. To prevent any failure of the demagnetization, I preferably employ in connection therewith hammers 46, which are carried by the frame 47, pivoted at 37 and having the cross-piece 48, which engages 50 with the cam 49, secured on the shaft 26. This cam raises the hammer gradually, but allows it to fall very abruptly, the effect of gravity being increased, if desired, by the coiled springs 50, coöperating with the frame 47 and put under tension as it is raised. The striking of the cores of the electromagnets by 55 these hammers serves to release the blanks certainly not only by the demagnetization, but also by the ordinary physical jar, the lat-

ter feature of which might be employed in connection with permanent magnets.

To prevent the blanks which have been advanced by the pawls 32 from being carried back by friction therewith, I may employ, in connection with each space, one or more electromagnets 51, which may be continually energized, but which are preferably in circuit with the magnets 33, so that they are energized only while the bars 31 are moving outward to receive fresh blanks. The lift of 75 these magnets 51 may be adjusted so as to simply overcome the effect of friction, or it may be adjusted so that the blanks will be raised entirely off of the bars 31. These magnets 51 are conveniently supported from cross-pieces 52, which are held in position upon the brackets 53, extending up from the angle-irons 30. To permit the movement of the angle-irons, the cross-pieces 52 are connected therewith by pin-and-slot connections, as 80 shown at 53^a.

In the preferred form of my invention, which is illustrated more especially in Fig. 10, instead of employing ordinary electromagnets I employ solenoids 33^b, with the 90 cores loose therein and adapted to drop down on the blanks, while the coils remain stationary, being supported by a cross-piece 34^b, suitably supported from the side pieces. I arrange the circuit so that it is broken just as 95 the bars 31 reach their outermost position, and the blank 23, with its attached cores, drops onto the bars 31 in advance of the hooks by which the blanks are carried away from the cores, which then drop the remaining distance 100 and rest upon the uppermost blank. As soon as the bars 31 are drawn from over the pile of blanks the circuit is closed, and the pull of the solenoid lifts the cores and the attached blank above the plane of the top of the bars 105 31, thus dispensing with the mechanism shown in Figs. 1 to 4 for lifting the magnets with the attached blanks. To insure the lifting up of the blank with the cores, I may insert in the center of the soft-iron core a small permanent bar-magnet, which will always adhere to the blank, but not with sufficient force to seriously resist the action of the bars 31 in pulling it loose. The strength of the current 110 in this form is adjusted so that the lifting force of the solenoids will be just sufficient to carry up a single blank; but if more than one blank adheres the strength of the current will not be sufficient to lift them, and they will 115 stay down, this electric balance, as it were, taking the place of the physical balance shown in Figs. 1 to 6. A simple arrangement of the circuit for this and the other form is shown in Fig. 7, where the solenoid-wire 33^b is in circuit with a resistance 54, by which the 120 exact amount of current necessary to secure the balance described can be applied, an ammeter 55 being included in the circuit, so that 125

in case the current should become reduced the attendant can know when a sufficient amount of resistance has been thrown out, the exact current necessary to the proper operation being of course known to the attendant. To make and break the circuit at each rotation of the shaft 26, I secure on the under side of the bar 42 two separated contacts 56, which rest on a disk 57, secured on the shaft 26, half of which is insulated, so that the circuit will be closed during half of the rotation of the shaft and opened the other half. In case the construction shown in Figs. 1 to 5 is employed the tilting of the arm 42 will raise the contacts 56 off of the disk 57 and break the circuit in case two or more blanks are lifted. A modification of this construction is indicated in Fig. 9, where instead of breaking the circuit in case it is overbalanced I employ an additional contact 58, which slides over an additional resistance 59, so as to automatically decrease the lifting power by thus throwing in additional resistance in case more than one blank is lifted. With this modification the contacts 56^a will have to coöperate with a segmental plate 57^a, so as to permit a considerable movement of the arm 42 without breaking the circuit at that point.

Referring now to Fig. 10, I have therein illustrated certain additional mechanism by which the operation of the feed apparatus is controlled under certain contingencies. With this construction the solenoid-lifter 33^b, with the movable cores, is employed, and the connections of the circuit *d*, in which it is included, are substantially the same as those shown in Fig. 7, except that the arm 42 is omitted, as the electrical balance is employed. In case the apparatus by which the blanks are kept at a certain level does not work satisfactorily I employ mechanism and alarms to either correct the difficulty or call the attendant's attention, so that he may correct it in case no automatic mechanism for correcting it is employed. If the mechanism should feed too rapidly and the supply of blanks become too high, I employ two contacts 60 and 61, which terminate in position so that if the blanks are at the proper level they are just below or possibly on a level with the contact 60, which is separated from the contact 61 by a space of more than the thickness of a sheet of tin, so that the circuit is not closed as a single sheet of tin is lifted. It will be apparent that I might use these contacts for breaking the main circuit if two or more sheets of tin were lifted by separating the contacts sufficiently so that they would not be closed by the passage of one sheet, but would be closed by the passage of two or more. In the present construction, however, I arrange to have the contacts closed when the pile gets high enough to begin to interfere with the movement of the bars 31. These contacts 60 and 61 are an electrical circuit *c*, which includes

a solenoid 62, carried by the lever 24 and having its core 63 secured to the pawl 27, so that when the circuit is closed the pawl is lifted out of engagement with the teeth of the wheel 28, and the upward feeding of the blanks ceases until the pile is lowered sufficiently to break the circuit, when the spring 64 or gravity carries the pawl 27 back into engagement with the wheel 28 and the feeding of the blanks is resumed. This circuit also includes an alarm 65, which begins to ring and calls the attention of the attendant to the fact that the blanks are above the normal level, which may be produced by a failure of the feeding mechanism to carry them off, so that he can remedy the difficulty. If, on the other hand, the supply of blanks should fall too low, I employ a contact 66, which is insulated from the pile of blanks and which has a pivoted contact 67 coöperating therewith and held out of engagement therewith by the blanks when they are above or at the proper level. When they get too low, the contact 67 falls on 66 and the circuit is closed through the alarm-bell 65, but not the solenoid 62, so that the attention of the attendant is called, but the operation of the blank-supply mechanism is not stopped.

It is desirable to employ an alarm-bell by which the attendant can be advised of the fact that the supply of blanks is nearly exhausted by the plate 18 nearing the upward limit of its movement, and in case the attendant does not respond before the supply is entirely exhausted it is desirable to have the machine automatically stopped. To effect this result, I employ another circuit *c*, in which is a contact 68, carried by the bottom of the plate 18, and coöperating therewith is a contact 69, which is held in engagement therewith by a spring, provided the number of blanks resting on the top of the vertical rod 70, sliding through the plate 18, is small. If the weight of the blanks is great, the contacts will be held apart. When the supply of blanks is sufficiently reduced, the circuit is closed and the alarm-bell 71, which is preferably of a different tone from 65, so that the attendant may distinguish between them, is rung. If the attendant does not replenish the supply in time, when the last blank is removed the contact 72, which is similar to 69, but weaker, so that it will be held away from the contact 68 by a single blank, is closed, and the solenoid 73 in this circuit is energized and its core 74, which is connected to the belt-shifting lever 75, is pulled in and the belt 76 is thrown from the driving-pulley 77 to the idle pulley 78 and the machine is stopped. It will be apparent that the effect of closing the circuit when the supply is reduced or entirely exhausted might be effected by contacts properly positioned to be closed by the advance of the plate 18 to a certain specific point, thus dispensing with the spring mechanism shown.

While I have shown and described my invention as embodied in the forms which I at present consider best adapted to carry out its purposes, it will be understood that it is capable of some modifications and that I do not desire to be limited in the interpretation of the following claims except as may be necessitated by the state of the prior art.

What I claim as new, and desire to secure by Letters Patent of the United States, is—

1. In a blank-feeding apparatus, the combination with the blank-holder, of means for raising the blanks therein, means for carrying away the blanks one by one as they are separated, a driving-shaft, a vertically-movable support, lifters carried by said support, a cam on the driving-shaft, and a lever coöperating with the cam and engaging the support to raise the lifters at each operation of the machine to separate a blank from the pile beneath.

2. In a device of the class described, the combination with the blank-holder, of means for raising the blanks therein, means for carrying away the blanks one by one as they are separated, a driving-shaft, a vertically-movable support, lifters carried by said support, a pair of cams located near the ends of the driving-shaft, a pair of levers having lugs thereon engaging with the cams, and connections between said levers and support so that both ends of said support will be raised uniformly to operate the lifters.

3. In a device of the class described, the combination with the blank-holder, of the electromagnetic separator, an electric circuit in which the separator is included, a rotating shaft, two circuit-terminals adjacent thereto, and a circuit-closing support carried by said shaft and closing the circuit through said terminals at each rotation.

4. In a device of the class described, the combination with the blank-holder, of the electromagnetic solenoid, the core adapted to rest on the blanks, an electric circuit including the solenoid, means for energizing the solenoid at regular intervals to lift the core and attached blank, and a member adapted to carry away the lifted blanks one by one.

5. In a device of the class described, the combination with the blank-holder, of the electromagnetic separator, means for energizing said separator at regular intervals, and mechanism for striking the core of said separator after the energization has ceased.

6. In a device of the class described, the combination with the blank-holder, of the magnetic separator, and means for striking said separator a sharp blow to insure the release of the blank.

7. In a device of the class described, the combination with the blank-holder, of the electromagnetic solenoid, the core adapted to rest on the blanks and having a permanent magnet carried thereby, an electric circuit includ-

ing the solenoid, means for energizing the solenoid at regular intervals to lift the core and attached blank, and a member adapted to carry away the lifted blanks one by one.

8. In a device of the class described, the combination with the blank-holder, of the electromagnetic separator, an electric circuit in which the separator is included, means for breaking the circuit at regular intervals, and mechanism for automatically breaking the circuit as the separator advances if it carries more than one blank.

9. In a device of the class described, the combination with the blank-holder, of the electromagnetic separator, an electric circuit in which the separator is included, means for breaking the circuit at regular intervals, and mechanism for automatically breaking the circuit as the separator advances if it carries more than one blank, consisting of a balance mechanism adapted to be overweighted by extra blanks.

10. In a device of the class described, the combination with the blank-holder, of the separator, and a balance mechanism coöperating therewith to release any extra blanks.

11. In a device of the class described, the combination with the blank-holder, of the separator, a balance mechanism upon which it is mounted, and means for releasing the attraction of the separator if the balance is destroyed.

12. In a device of the class described, the combination with the blank-holder, of the separator, an adjustable balance mechanism upon which it is mounted, and means for releasing the attraction of the separator if the balance is destroyed.

13. In a device of the class described, the combination with the blank-holder, of the electromagnetic separator, an electric circuit in which the separator is included, means for breaking the circuit at regular intervals, mechanism for automatically breaking the circuit as the separator advances if it carries more than one blank, said mechanism consisting of a balance adapted to be overweighted by extra blanks.

14. In a device of the class described, the combination with the blank-holder, of the electromagnetic separator, means for energizing said separator at regular intervals, and means for automatically diminishing the current if the separator carries more than a single blank.

15. In a device of the class described, the combination with the blank-holder, of the electromagnetic separator, means for energizing said separator at regular intervals, and means for automatically diminishing the current if the separator carries more than a single blank, said means consisting of a balance mechanism coöperating with resistance to increase the resistance as the balance is destroyed.

16. In a device of the class described, the combination with the blank-holder, of a ver-

tically-reciprocating frame, a balance pivoted in said frame, an adhering lifter carried by said balance, and means for automatically destroying the adhesion of the lifter if the 5 weight of the blanks adhering thereto is too great.

17. In a device of the class described, the combination with the blank-holder, of the electromagnetic separator, means for energizing 10 said separator at regular intervals, and means for striking the core of said separator after the energization has ceased, said means consisting of a pivoted hammer and a rotating cam to raise it and allow it to descend abruptly.

18. In a device of the class described, the combination with the reciprocating carrier having the dogs to advance the blanks, of the magnets to prevent the return of the blanks 20 with the carrier.

19. In a device of the class described, the combination with the reciprocating carrier having the dogs to advance the blanks, of the electromagnets to prevent the return of the 25 blanks with the carrier, and means for breaking the circuit while the carrier moves forward.

20. In a device of the class described, the combination with the blank-holder, of means 30 for separating the blanks one by one, means for carrying away the blanks, the vertically-moving support upon which the blanks rest, the rack-bar connected to said support, a shaft, a pinion on said shaft engaging the 35 rack-bar, a ratchet-wheel on said shaft, an operating-lever for the ratchet-wheel, a pawl carried by the operating-lever engaging the ratchet-wheel, a stop-pawl also engaging the ratchet-wheel, and a driving-shaft having a 40 cam thereon serving to operate the pawl-carrying lever.

21. In a device of the class described, the combination with the blank-holder, of the electromagnetic separator, an electric circuit in 45 which the separator is included, an adjustable resistance in the circuit by which the magnetic force may be regulated, and means for breaking the circuit at regular intervals.

22. In a device of the class described, the 50 combination with the blank-holder, of the vertically-movable support adapted to raise the blanks in said holder, a rack-bar connected to said support, a shaft, a pinion on said shaft, a ratchet-wheel on said shaft, an operating-lever 55 for the ratchet-wheel, a pawl engaging the ratchet and carried by the lever, a stop-pawl also engaging the ratchet, a driving-shaft, a lifter-support, lifters carried by said support, a lever coöperating with the lifter-support, and cams on the driving-shaft adapted 60 to swing the levers and raise the lifters and actuate the rack-bar; substantially as and for the purpose described.

23. The combination with the blank-holder, 65 of means for raising the blanks therein, means

for carrying away the blanks one by one as they are separated, a driving-shaft, a vertically-moving lifter-support, lifters carried by said support, a cam on the driving-shaft, a lever coöperating with the cam and engaging 70 the lifter-support, and means for controlling the rate of raising the blanks therein.

24. In a device of the class described, the combination with the machine, of the loose and driving pulleys thereon, a belt-shifter, 75 the automatic blank-feed apparatus therefor, and means set in motion by the removal of the last blank for moving the belt-shifter, said means consisting of an open circuit closed by the removal of the last blank, and an electromagnet in said circuit acting on the belt-shifter.

25. In a device of the class described, the combination with the machine, of the loose and driving pulleys thereon, a belt-shifter, 85 the automatic blank-feed apparatus therefor, and means set in motion by the removal of the last blank for moving the belt-shifter, said means consisting of an open circuit closed by the removal of the last blank, and an electromagnet in said circuit acting on the belt-shifter through a swinging lever terminating 90 in a yoke embracing the belt and a curved solenoid-core on the other end coöperating with said electromagnet.

26. In a device of the class described, the combination with the machine, of the automatic blank-feed apparatus therefor, and means for sounding an alarm when the blank-supply is about exhausted.

27. In a device of the class described, the combination with the machine, of the automatic blank-feed apparatus therefor, and means for sounding an alarm when the blank-supply is about exhausted, consisting of a 105 circuit containing an alarm and spring-contacts held apart by a certain weight of blanks.

28. In a device of the class described, the combination with the machine, of the automatic blank-feed apparatus therefor, means 110 for sounding an alarm when the blank-supply is about exhausted, and means for automatically stopping the machine when the blanks are entirely exhausted.

29. In a device of the class described, the combination with the machine, of the automatic blank-feed apparatus therefor, an electric circuit containing an alarm and an electromagnet, and two sets of open contacts in said circuit, one set being closed when the 115 supply of blanks is nearly exhausted and serving to ring the alarm, and the other set being closed by the removal of the last blank and serving to utilize the electromagnet to set in motion mechanism to stop the machine.

30. In a device of the class described, the combination with operating mechanism for keeping the supply of blanks at a certain level, said mechanism including a ratchet-wheel and a swinging actuating-pawl, of means for stop- 130

ping the operation of said mechanism if the supply exceeds a certain level, consisting of an electromagnet adapted to attract the pawl and carry it from engagement with the ratchet-
5 wheel when the circuit is closed by the position of the blanks.

31. In a device of the class described, the combination with operating mechanism for keeping the supply of blanks at a certain level, 10 of means for stopping the operation of said mechanism and sounding an alarm if the supply exceeds a certain level.

32. In a device of the class described, the combination with operating mechanism for 15 keeping the supply of blanks at a certain level, of means for stopping the operation of said mechanism and sounding an alarm if the supply exceeds a certain level, including an electric circuit whose closing is controlled by the 20 position of the blanks.

33. In a device of the class described, the combination with operating mechanism for keeping the supply of blanks at a certain level, of means for stopping the operation of said 25 mechanism and sounding an alarm if the supply exceeds a certain level, until said supply has reached its normal level.

34. In a device of the class described, the combination with operating mechanism for 30 keeping the supply of blanks at a certain level, of means for stopping the operation of said mechanism and sounding an alarm if the supply exceeds a certain level, until said supply has reached its normal level, said means including an electric current whose closing is 35 controlled by the position of the blanks.

35. In a device of the class described, the combination with operating mechanism for keeping the supply of blanks at a certain level, 40 of means for sounding an alarm if the supply falls below a certain level.

36. In a device of the class described, the

combination with operating mechanism for keeping the supply of blanks at a certain level, of delivery mechanism for carrying the blanks 45 away from said supply one by one, and means for sounding an alarm if the operating mechanism ceases.

37. In a device of the class described, the combination with operating mechanism for 50 keeping the supply of blanks at a certain level, of means for stopping the operation of said mechanism if the supply exceeds a certain level and for sounding an alarm if the supply falls below a certain level.

38. In a device of the class described, the combination with operating mechanism for keeping the supply of blanks at a certain level, of means for sounding an alarm if the supply 55 falls below a certain level and for sounding 60 an alarm and stopping the operation of said mechanism if the supply exceeds a certain level.

39. In a device of the class described, the combination with operating mechanism for 65 keeping the supply of blanks at a certain level, of means for sounding an alarm if the supply falls below a certain level, said means consisting of an open circuit containing an alarm, and contacts held apart by the blanks when they 70 are above a certain level.

40. In a device of the class described, the combination with operating mechanism for keeping the supply of blanks at a certain level, 75 of controlling mechanism connected therewith and including an open electric circuit having contacts adjacent to the normal level and separated by a greater distance than the thickness of the blank.

JOHN HOWARD McELROY.
